Specification for Design.

Patented May 30, 1916.

Application filed March 14, 1916. Serial No. 84,230. Term of patent 7 years.

To all whom it may concern:

Be it known that I, MICHAEL J. McINTYRE, a citizen of the United States, residing at Buffalo, in the county of Erie and State of New York, have invented a new, original, and novel Design for Game-Boards, of which the following is a specification, reference being had to the accompanying drawing, forming part hereof.

The figure is a plan view of the game board, showing my new design.

I claim:

The ornamental design for a game-board as shown.

MICHAEL J. McINTYRE.
